CLUB HEAD FOR GOLF PUTTER OR THE LIKE

Jerome P. McGranaghan, 1101 Prince St.,
Alexandria, Va.

Filed June 6, 1961, Ser. No. 65,478

Term of patent 14 years

(Cl. D34—5)

Fig. 1.

Fig. 2.

Fig. 3.

Fig. 4.

Fig. 5.

The side of the club head not shown is substantially the same as the side shown in FIGURE 2.

I claim:

The ornamental design for a club head for golf putter or the like, substantially as shown and described.
